Primary Examiner — Marianne Pandozzi(74) *Attorney, Agent, or Firm* — Barnes & Thornburg LLP(57) **CLAIM**

What is claimed is the ornamental design for a beverage dispenser, as shown and described.

DESCRIPTION

FIG. 1 is a perspective view of the beverage dispenser;
FIG. 2 is a front elevational view thereof;
FIG. 3 is a left side elevational view thereof;
FIG. 4 is a right side elevational view thereof;
FIG. 5 is a rear elevational view thereof;
FIG. 6 is a top plan view thereof; and,
FIG. 7 is a bottom plan view thereof.

The broken lines depict portions of the beverage dispenser that form no part of the claimed design.
